Inventor:-
Alfred Reeves,
By: B. Singer, Atty.

UNITED STATES PATENT OFFICE.

ALFRED REEVES, OF BIRMINGHAM, ENGLAND, ASSIGNOR OF ONE-HALF TO BUTLERS, LIMITED, OF BIRMINGHAM, ENGLAND.

HINGE FOR LENS-BEZELS OF MOTOR-CAR LAMPS.

1,367,204.

Specification of Letters Patent.

Patented Feb. 1, 1921.

Application filed July 7, 1919. Serial No. 309,066.

To all whom it may concern:

Be it known that I, ALFRED REEVES, a subject of the Kingdom of Great Britain, residing at 133 Sommerville road, Small Heath, Birmingham, in the county of Warwick, England, works' manager, have invented certain new and useful Improvements Relating to the Hinges for Lens-Bezels of Motor-Car Lamps, and which improvements are applicable to hinges for boxes and the like, of which the following is a specification.

This invention relates more particularly to the hinges of the lens bezels of motor car lamps, but is applicable to hinges for boxes and the like, the improvements comprising a hinge which is entirely contained within the lamp or other article in connection with which it is used, the object being to avoid any projections on the outer surface of the lamp or other article to which the hinge is applied.

According to the present invention, the axis of the hinge is located inwardly of the external surface or contour of the lamp or other body. One limb of the hinge is cranked or bowed to accommodate one of the edges at the joint when the hinge is in the open condition. This lamp may if desired involve an articulation.

In order that this invention may be clearly understood and readily carried into practice, reference may be had to the appended explanatory two sheets of drawings, upon which:—

Figure 1 illustrates a lamp constructed according to the present invention, with the bezel in the closed position.

Fig. 2 is a part sectional plan of the lamp shown in Fig. 1.

Fig. 3 is a part sectional plan of the lamp shown in Figs. 1 and 2 with the bezel in the open position.

Fig. 4 illustrates separately the hinge shown in Figs. 2 and 3.

Fig. 5 is a similar view to Fig. 2 but illustrating a modification.

Fig. 6 is a similar view to Fig. 2 but showing a further modification.

Fig. 7 illustrates the modification shown in Fig. 6 with the bezel in the open position.

In an embodiment of this invention, in which the hinge is adapted to be used in conjunction with the head lamp of a motor

vehicle, the lens bezel ring *a* is adapted to fit over a rim *b* which is fitted and secured in the body opening, so as to project in front of the body of the lamp. At the point at which the hinge is to be situated, the rim *b* is formed with a square, rectangular, or other aperture between the edge of the body and the front flanged edge of the rim.

One part of the hinge comprises a plate *c* which is secured to the inside of the body *d* of the lamp, as for instance by rivets *j*. The movable limb *e* of the hinge is articulated to the plate *c* at a position *f* adjacent to the edge of the body *a*.

The movable limb *e* of the hinge which is attached to the bezel ring *a* is of V-formation, the arm *g* of the V being flanged at *h* and secured to the inside of the bezel ring, as for instance by rivets *i*. The aperture in the rim accommodates the movement of the V-shaped limb of the hinge when opening and closing, the hinge pivot being so arranged in relation to the joint between the bezel and the body that upon the initial operation of the opening of the bezel, the edge *g* of the bezel which abuts against the edge of the body at a point adjacent the hinge is caused to clear the abutting edge of the body part of the joint. In Fig. 3 I have indicated in broken lines the path of the edge of the bezel in opening. The respective edges of the body *b* and bezel *a* at the joint may if desired be curved to this arc of movement so that while free opening and closing is permissible, a perfect joint is obtained when the bezel is in the closed condition.

For the purpose of stabilizing the hinge, one end of a link *k* is hinged to the V limb near the apex of the V, the other end of such link being hinged to one end of a second link *l*, the other end of which second link is hinged to the plate *c* to which the V limb is hinged.

If desired, the links *k*, *l* may be adapted to form the means by which the opening movement of the bezel is limited.

Fig. 5 illustrates an embodiment which resembles that illustrated in Figs. 2, 3 and 4, with the exception that the links *k* and *l* are omitted.

In the embodiments illustrated in Figs. 6 and 7, instead of employing a rigid limb *e*, *g*, I employ a limb *m*, *n* having an articulation at *o*, the part *n* of the limb being appropriately secured to the bezel *a* and the

part *m* of the link being pivoted to a plate *p* appropriately secured to the lamp body *d*.

What I claim as my invention and desire to secure by Letters Patent is:—

- 5 1. A lamp body open at one side, a rim around said opening and arranged on the inner side and projecting from the edge of the wall of the body, said rim having an opening, a bezel ring at the open side 10 of the body, corresponding to the contour thereof and when closed abutting against the edge of the wall of the body, and a hinge for said ring arranged with its pivotal axis within the external contour of the 15 body, so that the hinge is contained within the lamp when the ring is in closed position, said hinge having an arm attached to the

inner side of the bezel ring and operating in said opening of the rim.

2. A lamp body open at one side, a bezel ring at the open side of the body corresponding to the contour thereof and when closed abutting against the edge of the wall of the body, and a hinge for said ring arranged with its pivotal axis within the external 25 contour of the body so that the hinge is contained within the lamp when the ring is in closed position, said hinge comprising a quadrilateral structure hinged at its four corners and including an arm attached to 30 the inner side of the bezel ring.

In witness whereof I have hereunto set my hand.

ALFRED REEVES.
